(57) **CLAIM**

The ornamental design for a perforating device, as shown and described.

DESCRIPTION

FIG. 1 is a front perspective view of a perforating device, according to a first embodiment of a new design.

FIG. 2 is a front elevational view thereof;

FIG. 3 is a left side elevational view thereof;

FIG. 4 is a rear elevational view thereof;

FIG. 5 is a right side elevational view thereof;

FIG. 6 is a bottom plan view thereof;

FIG. 7 is a top plan view thereof;

FIG. 8 is a front perspective view of a perforating device, according to a second embodiment of a new design.

FIG. 9 is a front elevational view thereof;

FIG. 10 is a left side elevational view thereof;

FIG. 11 is a rear elevational view thereof;

FIG. 12 is a right side elevational view thereof;

FIG. 13 is a bottom plan view thereof; and,

FIG. 14 is a top plan view thereof.

The broken lines in the drawings depict portions of the perforating device that form no part of the claimed design.

1 Claim, 14 Drawing Sheets
